CONTAINER CLOSURE

Henry B. Korwan, Brooklyn, N. Y., assignor to
 American Can Company, New York, N. Y., a
 corporation of New Jersey

Application December 10, 1934, Serial No. 756,876

5 Claims. (Cl. 220—42)

The present invention relates to container closures and has particular reference to an improved container closure construction which includes a closure capable of a multiplicity of sealing functions.

An object of the invention is the provision of an outer closure for containers which is used as a protector for an inner closure during storage and shipment of the container and which is so constructed that it serves as a reclosure and also provides successive or multiple seals for a container before and after the removal of the inner closure.

Another object is the provision of such a multiple service outer closure which has two container engaging walls or wall sections capable of closing a container in two different sealing positions.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a container and closure embodying the instant invention showing the outer cover in separated relation to the container and inner closure;

Fig. 2 is an enlarged fragmentary sectional view showing the outer cover applied to the container over the inner closure; and

Fig. 3 is a similar view showing the outer cover utilized as a reclosure after the inner closure has been removed.

As a preferred embodiment of the invention the drawing discloses the invention applied to a nozzle type of container comprising a tubular body 11 (Fig. 1), closed at its bottom by an end closure secured in any suitable manner as by a seam 12.

The upper end of the container is closed by an end closure 13, which is secured to the upper edge of the body in any suitable manner as by a seam 14.

The top closure 13 is provided with an opening 15 (Fig. 1) in which a round and tapered dispensing nozzle 16 is carried, the nozzle being secured to the edge of the closure defining the opening in any suitable manner, as by soldering, welding or crimping. The upper edge of the nozzle is preferably rolled outwardly in a curl 17 (Fig. 2) providing a smooth top edge or closure receiving seat surrounding its open mouth. This nozzle mouth or dispensing opening is closed by an inner closure or seal 18 which may be frangible and is preferably crimped over the curl 17,

the marginal edge of the seal being rolled around the curl in tight fitting engagement and extends down over the outside of the curl and terminates in a straight portion engaging the nozzle side wall under the curl.

An outer closure or auxiliary cover 25, provided for protection of the inner seal, fits over the nozzle 16 and inner seal 18 during storage and shipment of the container and is also adapted to be utilized as a reclosure when the inner seal has been broken or removed. This outer cover comprises a paneled top wall 26 which merges into a curved wall 27 corresponding in curvature with the nozzle curl 17. The curved wall merges into a depending flange or wall 28, 15 having two wall sections of different diameter, i. e. a wall section 29 which has an inside diameter substantially equal to the outside diameter of the curl 17, and a wall section 30 which is connected with the section 29 by a curved shoulder 31 20 and has an inside diameter substantially equal to the outside diameter of the curl 17, plus the thickness of the seal 18 crimped over the curl 17. This latter wall section terminates in an outwardly rolled curl 32.

During storage and shipment of the container, the applied outer cover fits securely over the nozzle with the wall section 30 and shoulder 31 of the flange 28 in tight frictional engagement with the outside periphery of the inner seal 18 as shown in Fig. 2, thus protecting the seal against accidental opening.

When the contents of the container are to be used, the seal 18, which may be frangible or readily removable, is broken or removed from its seat or curl 17. This leaves the container or the nozzle of the container with a smaller sealing seat, which would cause the ordinary outer cover when used as a reclosure to fit too loosely on the container or nozzle. It is to prevent this condition that the outer cover or closure is provided with two wall sections of different diameter, so that when the inner closure or seal is removed the same cover may be used as a reclosure.

When so utilized, the curved wall 27 of the outer cover fits over the curl 17, with the wall section 29 tightly engaging the outside periphery of the curl, as shown in Fig. 3. It is thus obvious that with this improved construction the outer cover will at all times fit tightly over the nozzle, 45 protecting the seal when used as an inner closure and protecting the container contents when utilized as a reclosure.

It will be understood that the use of the invention is not restricted to containers having nozzles 55

but is equally applicable to a variety of containers having dispensing openings similar to the nozzle 16.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container closure construction, comprising a container having a dispensing opening defined by a closure receiving seat, a removable seal closing said opening and engaging said seat and an auxiliary closure covering said seal and having spaced wall sections of different diameters corresponding to the respective diameters of said seal on said seat and said seat alone, one of said wall sections being adapted to closely engage said seal on its seat and the other wall section being adapted to closely engage said seat after removal of said seal.

2. A container closure construction, comprising a container having a dispensing opening defined by a closure receiving seat, a removable inner seal closing said opening and secured to said seat, an outer closure to protect said seal and to serve as a reclosure after removal of said seal, said outer closure having a plurality of spaced portions of varying diameters for respec-

tively engaging said seal on said seat and said seat alone after said seal is removed.

3. A container closure construction, comprising a container having a dispensing opening defined by a closure receiving seat, an inner seal secured to said seat and closing said opening and an outer closure to cover said inner seal and to serve as a reclosure in the absence of said seal, said outer closure having a plurality of spaced sealing parts each having a different diameter, one of said parts adapted to sealingly engage said seal before its removal from the container, and the other part adapted to sealingly engage said seat in the absence of said seal.

4. A container having a plurality of sealing parts of different diameters and a closure adapted to also serve as a reclosure and having parts of different diameters corresponding to the diameters of said container sealing parts, only one of said closure parts being in sealing engagement with its corresponding container sealing part at one time.

5. A container closure construction, comprising a dispensing outlet, a removable seal covering said outlet and extending over the sides thereof, and a cover for said outlet and seal, said cover having a depending flange having a large diameter section for engaging tightly over said seal when the latter is applied to said outlet and having a small diameter section for engaging tightly over said outlet when said seal has been removed therefrom.

HENRY B. KORWAN:
